(57) **CLAIM**

The ornamental design for a golf club head, as shown and described.

DESCRIPTION

FIG. 1 is a bottom plan view of a golf club head embodying the inventive design.

FIG. 2 is a top plan view thereof.

FIG. 3 is a heel-side elevational view thereof.

FIG. 4 is a toe-side elevational view thereof.

FIG. 5 is a rear elevational view thereof.

FIG. 6 is a front elevational view thereof; and,

FIG. 7 is a top rear perspective view thereof.

The broken lines immediately adjacent the shaded areas represent the bounds of the claimed design, while all other broken lines are directed to environment and are for illustrative purposes only; the broken lines form no part of the claimed design.

1 Claim, 7 Drawing Sheets

FIG. 1
